UNITED STATES PATENT OFFICE.

MILTON E. MYERS, OF GLOVERSVILLE, NEW YORK, ASSIGNOR, BY MESNE ASSIGNMENTS, TO VOGUE GLOVE COMPANY, INC., OF GLOVERSVILLE, NEW YORK, A CORPORATION OF NEW YORK.

DESIGN FOR A MITTEN.

Application filed April 5, 1927. Serial No. 21,463. Term of patent 14 years.

To all whom it may concern:

Be it known that I, MILTON E. MYERS, a citizen of the United States of America, residing at Gloversville, in the county of Fulton and State of New York, have invented a new, original, and ornamental Design for a Mitten, of which the following is a specification, reference being had to the accompanying drawings, forming part thereof.

Figs. 1 and 2 of the drawing are respec-

tively views showing the back and palm of a mitten to the back of which are secured elements to produce the effect of eyes, nose and ears, and which with the surface thereof gives the appearance of the face of an animal.

I claim:

The ornamental design for a mitten as shown and described.

MILTON E. MYERS.
